UNITED STATES PATENT OFFICE.

SAMUEL H. PETERS, OF ALLENTOWN, PENNSYLVANIA.

MAIL-BOX FASTENER.

1,067,133.

Specification of Letters Patent.

Patented July 8, 1913.

Application filed October 1, 1912. Serial No. 723,393.

To all whom it may concern:

Be it known that I, SAMUEL H. PETERS, a citizen of the United States, residing at Allentown, in the county of Lehigh and State of Pennsylvania, have invented new and useful Improvements in Mail-Box Fasteners, of which the following is a specification.

My invention is an improved mail box and automatically acting locking means therefor and consists in the construction, combination and arrangement of devices hereinafter described and claimed.

The object of my invention is to provide an improved fastener which automatically locks the mail box when the latter is closed and which may be readily operated to unlock the box when it is desired to open the latter to remove mail therefrom.

20 In the accompanying drawings:—Figure 1 is a vertical sectional view of a mail box in closed position provided with my improved automatically operated fastening devices. Fig. 2 is a horizontal sectional view of the 25 same. Fig. 3 is a vertical sectional view of the same on the plane indicated by the line a—a of Fig. 1.

The body of my improved mail box comprises a main member 1 and a pivoted member 2 connected to the member 1 by a hinge lever. The member 1 comprises a back 2 and side walls 3. The member 1 has a top 5 provided with an opening 6 to admit mail matter and also has a hinge lid 7 to close the 35 said opening. Links 12 connect the members of the box, as shown.

In the upper end of the member 1 of the box and just below the top 5 is a rectangular frame 15, the rear side 16 of which is secured 40 to the back wall 3 by means of a screw or similar device 17 and the ends 18 of which are secured to the walls 4 by screws or similar devices 19. The front side of the bar 20 of said frame is spaced a suitable distance 45 from the front side of the upper end of the member 1 and is provided with a centrally arranged longitudinal slot 21.

The catch 22 is slidably mounted on the bar 20, this movement being controlled by a 50 stop screw 23 which operates in the slot 21 and the said catch having an inclined front surface 24. The catch is provided with an arm 25 which extends through an opening in one side wall of the box member 1 and is 55 provided at its outer end with a button or presser head 26. A rocker arm 27 is pivotally

mounted as at 28 on one end bar 18 of the frame 15 and is pivotally connected as at 29 to the arm 25 of the catch, the pivot 29 operating in an opening 30 with which the 60 said arm is provided. A rod 31 has one end pivotally connected as at 32 to the other end of the rocker-arm, the said pivot 32 operating in a slot or opening in one end of said rod, the said rod being mounted for longitudinal movement in a guide 33 with which the rear bar 16 of the frame 15 is provided and being provided with a head 34 which travels on said rear bar. A coiled spring 35 is placed on the said rod, one end of the said 70 spring bearing against the guide 33 and the other end thereof being engaged by a pin 36 and a washer 37 carried by said rod. Hence, the rod is moved in one direction by the spring and through the instrumentality of 75 the yoke 27 normally holds the catch 22 in locking position. The outer end of the rod 31 extends through an opening in one side of the box member 1 and has a head 38 which forms a stop to limit the movement of the 80 rod by the spring 35.

On the inner side of the front wall 8 of the box member 2, near the upper end thereof, is a bracket 39 in which is pivotally mounted a spring pressed latch 40 which, 85 when the box is closed engages the inclined or cam face 24 of the catch 22 and is caused to engage said catch and thereby lock the box in closed position. By pressing inwardly on the presser head 26, the catch may 90 be moved longitudinally a sufficient distance, against the tension of the spring 35 to be out of the path of and, hence, engage the latch 40 thereby unfastening the box and permitting the front member 2 thereof to be 95 turned downwardly to open position.

While I have herein shown and described a preferred form of my invention, I would have it understood that changes may be made in the form, proportion and construction of the several parts without departing from the spirit of my invention and within the scope of the appended claims. I would also have it understood that the parts of my box may be made of any suitable material 100 and that the box may be of any suitable form and size.

I claim:—

1. A mail box of the class described comprising a pair of members hinged together, 110 one of said members having a longitudinally movable catch, and means to cause said catch

to move to disengaged position, and a spring 5 pressed latch carried by the other member and adapted to engage said catch when the box is closed, the first mentioned member of the box being further provided with a frame on which said catch is mounted for longitudinal movement, a longitudinally movable rod also mounted on said frame, a spring acting on said rod to move the same in one 10 direction, and a rocker arm pivotally mounted on the same frame and connected to said rod and said latch.

2. A mail box of the class described comprising a pair of members hinged together, 15 one of said members having a longitudinally movable catch, and means to cause said catch to move to disengaged position, and a spring pressed latch carried by the other member and adapted to engage said catch when the

box is closed, the first mentioned member of the box being further provided with a frame on which said catch is mounted for longitudinal movement, a longitudinally movable rod also mounted on said frame, a spring acting on said rod to move the same in one 20 direction, and a rocker arm pivotally mounted on the same frame and connected to said rod and said latch, the rod and the latch being each provided with an arm extending through an opening in one side of 25 the first-mentioned member of the box.

In testimony whereof I affix my signature in presence of two witnesses.

SAMUEL H. PETERS.
